UNITED STATES PATENT OFFICE

2,362,849

CROWN CAP CONVEYER

Paul E. Pearson and Carl E. Magnus, Chicago, Ill., assignors to Continental Can Company, Inc., New York, N. Y., a corporation of New York

Original application March 6, 1941, Serial No. 382,056, now Patent No. 2,326,675, dated August 10, 1943. Divided and this application March 8, 1943, Serial No. 478,412

2 Claims. (Cl. 198—20)

The invention relates generally to the art of manufacturing crown caps and primarily seeks to provide a novel crown cap conveyer mechanism for feeding crown caps to a counting machine or to other crown cap handling mechanisms. This application constitutes a division of the previously copending parent case filed by Paul E. Pearson and Carl Magnus on March 6, 1941, for Crown cap counting mechanism, Serial Number 382,056 which issued as Patent 2,326,675 on August 10, 1943.

In the counting mechanism of the parent case above identified there is included a rotor having crown cap receiving seats equidistantly spaced about its marginal edge portions onto which crown caps are fed, presser plunger elements being vertically reciprocable over said seats for engaging and pressing caps on the seats and including actuator element portions each properly placed so as to be effective to actuate cap counting devices by contact of the associated plunger element with a crown cap and being displaceable from said effective position whenever said associated plunger moves toward the underlying seat and fails to engage a crown cap thereon. The present invention resides in providing a novel conveyer structure for feeding the crown caps one by one onto said rotor seats.

An object of the invention is to provide a conveyer structure of the character stated including novel conveyer means for receiving the crown caps en masse or in groups and delivering them one by one and in suitably spaced relation onto the rotor seats.

Another object of the invention is to provide a crown cap conveying means of the character stated including a wide belt on which the caps are fed side by side, a belt flight traversing the wide belt so as to divert caps to one side, a narrow belt flight to receive caps from the other belts and convey them single file, and means for taking caps from the narrow belt and delivering them one by one onto the receiving rotor seats.

Another object of the invention is to provide a conveyer or mechanism of the character stated in which said traversing belt flight is disposed diagonally across the wide belt and in which there is included a knurled rotor spaced a distance slightly greater than the diameter of the crown caps from the delivery end portion of the traversing belt and movable reversely of the direction of movement of said traversing belt so as to be effective to prevent jamming of caps as they pass from the wide belt onto the narrow belt.

With the above and other objects in view that

will hereinafter appear, the nature of the invention will be more fully understood by following the detailed description, the appended claims and the several views illustrated in the accompanying drawings.

In the drawings:

Figure 1 is a side elevation illustrating the invention.

Figure 2 is a plan view, parts of the cap presser 10 rotor being broken away to show some of the seats onto which the crown caps are fed.

Figure 3 is a fragmentary vertical cross section taken on the line 3—3 on Figure 2.

Figure 4 is a fragmentary vertical cross section taken on the line 4—4 on Figure 2.

Figure 5 is a fragmentary vertical cross section taken on the line 5—5 on Figure 2.

Figure 6 is a fragmentary vertical cross section taken on the line 6—6 on Figure 2.

Figure 7 is a fragmentary vertical cross section taken on the line 7—7 on Figure 2.

In the apparatus herein disclosed as an example of embodiment of the invention, the cap feeding means forming the basis of the present invention is generally designated A, and by this means the crown caps are fed from an assembling or spotting machine to the counting mechanism covered in the herein before mentioned parent case wherein is included a cap pressing and counter mechanism actuating unit generally designated B, and a counting mechanism or unit proper designated C. See Figure 2.

The feeding means A includes a bed frame 5 supported upon a standard 6 and from which is suspended an electric motor 7. The crown caps enter the apparatus en masse or in transverse rows on their way from the assembling or spotting machine to the counting mechanism on a wide belt 8, the delivery end of which passes over a support trough 9 and over a pulley 10. The pulley 10 is mounted on a cross shaft 11 which is rotatable in frame bearings 12 and carries a worm wheel 13 to which rotation is imparted by a worm gear 14 mounted on a driver shaft 15 rotatable in frame bearings 16. The shaft 15 also carries a large pulley 17 which is driven by a belt 18 from the motor drive pulley 19. See Figures 1, 2 and 6.

The belt 8 feeds the caps, hollow side uppermost, under a single layer confining shelf 20 and against an aligned belt 21 disposed diagonally across the belt 8 and which turns about a tensioning idler pulley 22 at the receiving side of the belt 21 and over a driver pulley 23 at the delivery side of said belt. The driver pulley 23

rotates in close proximity to the belt 8 and is carried at the lower end of a vertical shaft 24 rotatable in bearings 25 and driven through a bevel gear couple 26 by a driver shaft 27. See Figures 1, 2 and 6. The shaft 27 is rotatable in bearings 28 and is equipped with a pinion 29 to which rotation is imparted through an idler gear 30 from a driver gear 31 mounted on the cross shaft 11.

A knurled rotor 32 is opposed to the delivery end of the aligner belt 21, being spaced therefrom a distance just in excess of the diameter of the crown caps so as to cause the caps to pass in single file between said rotor and belt without jamming. The rotor 32 is mounted at the lower end of a shaft 33 rotatable in the vertically disposed frame bearing 34 and driven by pulley and belt connections 35 with the vertical extension of the shaft 24. See Figures 1, 2 and 6.

Crown caps passing single file between the delivery end of the aligner belt 21 and the jam preventing rotor 32 pass into the single file guide-way 36 and onto an endless conveyer 37 which passes over a tightener idler pulley 38 at its receiving end, and over a driver pulley 39 at its delivery end. The driver pulley 39 is affixed to one end of a driver shaft 40 rotatable in frame bearings 41 and having a worm gear 42 mounted thereon to which rotation is imparted by a worm gear 43 fixed upon a shaft 44. The shaft 44 is rotatable in frame bearings 45 and is releasably drive coupled, as at 46, with the shaft 15 hereinafter referred to. See Figures 2, 3 and 7.

The shaft 44 also carries a worm gear 47 which meshes with and imparts rotation to a worm wheel 48 mounted on a shaft 49 rotatable about a vertical axis in a bearing 50 in the casing unit 51 and which carries a spur gear 52 at its lower end and which serves to drive the turret or rotor 53 of the unit B by meshing with the rotor drive gear 54. See Figures 2 and 4.

At its delivery end, the conveyer belt 37 delivers the crown caps one by one into the peripheral pockets of a distributor disk 55 which is adjustably affixed to the upper end of a sleeve 56 rotatable about a stud shaft 57 fixed vertically in a frame bearing 58. The sleeve 56 carries a spur gear 59 to which rotation is imparted by the turret or rotor gear 54 to which, in turn, rotation is imparted by the gear 52 previously referred to. See Figures 2 and 5. While traveling about in the pockets of the distributor disk 55, the crown caps are retained by a surrounding wall 60 which extends to the discharge point 55

61 at which the crown caps are delivered one by one onto the seats 62 of the rotor 53 of the cap pressing, counter mechanism actuating unit B.

It is of course to be understood that the details of structure and the arrangement of parts may be variously changed and modified without departing from the spirit and scope of the invention.

We claim:

1. In crown cap conveyer means, a wide conveyer belt on which caps are fed side by side, a second conveyer belt having a flight disposed transversely over said wide belt for intercepting caps fed by said wide belt and moving them laterally over said wide belt to one side thereof, a narrow belt disposed to receive caps fed laterally on said wide belt and convey them single file away from said wide belt, and a diverter wall extending continuously and diagonally across the full width of the wide belt in advance of said second conveyer flight and a distance thereabove slightly greater than the thickness of a crown cap thereby to be effective to directly contact and strip off laterally any caps being conveyed by the wide belt in superposed relation.

2. In crown cap conveyer means, a wide conveyer belt on which caps are fed side by side, a second conveyer belt having a flight disposed transversely over said wide belt for intercepting caps fed by said wide belt and moving them laterally over said wide belt to one side thereof, a narrow belt disposed to receive caps fed laterally on said wide belt and convey them single file away from said wide belt, said second conveyer flight being disposed to traverse said wide belt diagonally, a knurled rotor rotating in a direction opposite the direction of travel of said second conveyer flight and spaced a distance slightly greater than the diameter of a crown cap from the end of the second conveyer flight where it delivers onto said narrow conveyer so as to prevent jamming of caps as they are being delivered onto said narrow conveyer, and a diverter wall extending continuously and diagonally across the full width of the wide belt in advance of said second conveyer flight and a distance thereabove slightly greater than the thickness of a crown cap thereby to be effective to directly contact and strip off laterally any caps being conveyed by the wide belt in superposed relation.

PAUL E. PEARSON.
CARL E. MAGNUS.
